CAR FOR AN AMUSEMENT DEVICE

Lee A. Sullivan, Jr., Jacksonville, Ill., assignor to Eli Bridge Company, Jacksonville, Ill., a corporation of Illinois

Application May 2, 1955, Serial No. 35,774

Term of patent 14 years

(Cl. D34—5)

FIG. 1

FIG. 2

FIG. 3

FIG. 4

Figure 1 is a side elevational view of a car for an amusement device showing my new design.

Fig. 2 is a top plan view thereof.

Fig. 3 is a front view thereof.

Fig. 4 is a rear view thereof.

I claim:

The ornamental design for a car for an amusement device, as shown.
